United States Patent Office

Des. 191,907
Patented Dec. 12, 1961

191,907

HAND RAILING

James C. Conradt and Clifford Leslie McDaniel, Hamilton, Ohio, assignors to L and J Specialty Corporation, a corporation of Ohio

Filed Mar. 3, 1959, Ser. No. 54,819

Term of patent 14 years

(Cl. D13—7)

FIG. 1

FIG. 2

FIG. 1 is a perspective view of a hand railing showing our new design, the central portion thereof being broken away to indicate an article of indefinite length; while the dotted lines indicate a bracket for illustrative purposes only, and

FIG. 2 is a sectional view taken along the line 2—2 of FIG. 1.

We claim:

The ornamental design for a hand railing, as shown and described.
